UNITED STATES PATENT OFFICE

2,436,139

STAIR COVER

James Clark, Akron, Ohio, assignor of one-third
to Donald Gottwald, Akron, Ohio

Application April 6, 1946, Serial No. 660,059

2 Claims. (Cl. 20—79)

1

The present invention relates generally to protective coverings and covering materials and particularly to a mat of novel design and construction for covering stairs and the like.

The mat of my invention meets a long standing demand for an article of unitary and homogeneous construction which is adapted to contact simultaneously, as a protective cover, surfaces in several planes, and to cover the intersections of such planes although the angles thus defined be of 90° or less. Mats of construction and design materially different from mine have been widely used for the purpose of covering stairs but, unlike my mats, have never been entirely satisfactory, to my knowledge. Mats of unitary construction have been most easily manufactured and apparently most desirable to use since they have long been generally employed and are presently probably the most important type commercially. There are two varieties of these, namely, the homogeneous and non-homogeneous. The former type has been used to some extent but because of its tendency to buckle and the difficulty in conforming this type to the sharp angles and to the various plane surfaces encountered in usual stair constructions, because of the difficulty of causing such mats to hug stairs for protracted periods and because of their limited durability and wear resistance, especially in the portion overlaying the stair bead, they have come into only limited use. The non-homogeneous mats characterized by those of composite construction, such as rubber-canvas in which the bead engaging and overlying portion is of canvas and the riser and tread engaging portions are of rubber and canvas, have been more generally employed because of the relative ease with which that may be permanently attached to stairs and the freedom from the tendency to buckle and pull away from the stair corners, edges or surfaces. These mats, however, have left much to be desired in that the bead covering portion, and especially the portion overlaying the external corner or edge of the stair, has very limited durability, being of canvas construction. Full use of the tread or riser covering portions of these mats is rarely realized and frequent replacement is required. The desirability of extending the life of these mats is thus obvious as is the hitherto apparent impossibility of so doing.

The mat of my invention exhibits no tendency toward failure in any portion before the full effective use of the tread overlying portion is substantially realized. Neither does my mat tend to buckle when secured to a stair nor to pull away

2

from engagement with the various surfaces, edges and corners of the stair, as aforementioned. Moreover, because of its construction and design, it tends actually to adhere to the contour of the stair, especially in the under portion of the ledge or overhang of the stair which is usually the most difficult portion to which to attach.

Referring to the drawings accompanying and forming a part of the invention:

Figure 1 is a prospective view of one form of mat of this invention attached to a stair;

Figure 2 is a plan view of the mat of Fig. 1;

Figure 3 is a side view in elevation of the mat of Fig. 1; and,

Figure 4 is a side elevation of the intermediate or bead engaging portion of the mat taken on line 4—4 of Fig. 2.

The illustrated mat M of my invention is a comparatively thin rectangular rubber sheet having greater width than length and comprising rectangular end portions 1 and 2 and rectangular intermediate portion 3.

End portion 1 is the tread engaging portion of the mat, as shown in Fig. 1, and therefore has the greatest surface area of the aforesaid three portions. This portion is provided with a substantially monoplanar under surface 4 and an upper surface 5, comprising a ribbed or corrugated center section 6 and a substantially smooth surface 7 bordering said ribbed section.

End portion 2 is similarly provided with a substantially monoplanar under surface 8, an upper surface 9 having a ribbed section 10 and a substantially smooth surface section 11 bordering said ribbed section. The ribbed section of this portion of the mat is provided to lend uniform appearance to the mat and, more importantly, its purpose is to extend the useful life of this portion of the mat, which is subject to less wear than the tread portion but suffers substantial wear nevertheless. Also, the ribs in the surface of this portion preserve the appearance of the mat, being less readily noticeably marked by wearing or scuffing contacts.

Intermediate portion 3 is the bead engaging portion of the mat, as illustrated in Fig. 1, where it is shown attached to and overlying the bead B defined by the riser R and tread T of the stair. This element of the mat comprises the portion between the two end portions and includes the relatively thin portion 12 of the mat and the adjacent portions extending to the borders of the end portions 1 and 2 of the mat. This intermediate portion has a substantially monoplanar

under surface 13 which is engaged with the bead as shown in Fig. 1, and a smooth unribbed upper surface 14 interrupted only by relatively thin or indented portion 12. Indented portion 12, as illustrated, extends the full width of the mat, is very narrow, of rectangular shape and, compared to the end portions of the mat, of a very small surface area. Actually, in the illustrated mat which is designed for use with a stair of standard dimensions, the width of indented portion 12 approximates $\frac{1}{8}$ inch, while its thickness, approximates three quarters of the mat thickness, which is about $\frac{1}{8}$ inch, and its length equals the mat width, i. e., about eighteen inches.

In the assembly of Fig. 1 the indented portion of the mat is engaged through its under surface 13 with the inside corner defined by the top of riser R and the opposed portion of the stair bead B. The tendency in this assembly is for the adjacent riser and bead covering portions of the mat to hug, as intended, the stair rather than to pull away or buckle as do the stair mats of the art, the riser covering portion being long enough to wedge between the stair treads adjacent above and below the riser, as shown in Fig. 3. It will be appreciated that the forces developed due to the depression in the surface of the mat at the critical point account for much of the advance and advantage of this mat over the mats of the prior art. It will likewise be appreciated that while my mat is thus shaped with this thin portion, it is not noticeably less strong in use than other mats since this reduction in its thickness has been effected in a portion of the mat which is not subject to the extent of wearing service that the other portions of the mat must suffer. I have, in fact, found that despite the existence of this relatively thinner section, my rubber mat is equally as strong and flexible and capable of enduring repeated stretching and bending operations without fatigue as any previously known rubber mats.

The illustrated form of mat of my invention is composed of natural rubber which has been treated in the customary manner to vulcanize it and render it suitable for uses demanding toughness and wear resistant characteristics. It is to be understood, however, that this mat may be composed of other elastomeric or rubber-like materials such as the so-called synthetic rubbers, and that it might comprise several different varieties of rubber or rubber-like materials. Furthermore, it is to be understood that this mat of my invention may be a composite article consisting of one or more of the aforementioned rubber-like materials and a fabric network or several independent or interlocking fabric layers. Preferably, however, the article is not composite, but is as shown since in that form it exhibits the most desirable strength and wear properties and is generally most readily and inexpensively manufactured and applied or used.

This mat of my invention is suitably attached to a stair or the like with rubber cement or an equivalent adhesive substance, or with nails, staples or the like, especially if it is of composite construction, as aforementioned, and therefore especially suitable for use with such latter securing means.

Having thus described the present invention so that those skilled in the art may be able to 10 understand and practice the same I state that my invention is defined in what is claimed.

What is claimed is:

1. A molded rubber stair mat comprising a portion for lying flat on a horizontal stair tread, a portion for lying flat against a vertical stair riser, and a portion between said tread and riser engaging portions to lie close to the front edge and underside of said tread and having a groove in its outer surface along which the mat may bend to fit into the angular space at the intersection of the tread and riser, said riser portion being long enough to wedge between adjacent stair treads whereby the mat may be positioned and maintained in snug engagement with the riser and bead of the stair.

2. In a stairway including a plurality of stairs comprising stair treads and risers between the treads, a plurality of stair mats defining a continuous covering for the stairway, said mats each being of molded rubber material and fabric composition and comprising a tread portion covering and engaging a stair tread, a riser portion covering a stair riser, and a bead portion between said tread and riser portions and having a groove in its outer surface along which said portion may bend to engage the undersurface of said tread and to fit into the angular space along the intersection of the bead and riser, said riser portion being long enough to wedge between adjacent treads whereby the mat may be maintained in snug engagement with the riser and bead of the stair.

JAMES CLARK.
